(57) **CLAIM**

The ornamental design for a bottle with sneaker tread base, as shown.

DESCRIPTION

FIG. 1 is a front, right perspective view of a first embodiment of a bottle with sneaker tread base showing our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a back, left perspective view thereof;

FIG. 9 is a front, right perspective view of a second embodiment of a bottle with sneaker tread base showing our new design;

FIG. 10 is a front view thereof;

FIG. 11 is a back view thereof;

FIG. 12 is a left view thereof;

FIG. 13 is a right view thereof;

FIG. 14 is a top view thereof;

FIG. 15 is a bottom view thereof; and,

FIG. 16 is a back, left perspective view thereof.

The broken lines in the drawings depict portions of the bottle with sneaker tread base that form no part of the claimed design.

1 Claim, 16 Drawing Sheets
